NECKTIE RACK

Knut G. Behlefeldt, Los Angeles, Calif.

Application February 18, 1955, Serial No. 34,569

Term of patent 14 years

(Cl. D33—8)

Fig. 1.

Fig. 3.

Fig. 2.

Fig. 1 is a perspective view of a necktie rack embodying my design, looking from the right side and above;

Fig. 2 is a perspective view thereof, looking from the left side and below; and

Fig. 3 is an end elevation thereof as viewed from the right in Figs. 1 and 2.

I claim:

The ornamental design for a necktie rack, as shown.
